UNITED STATES PATENT OFFICE

132,761

DESIGN FOR A TEXTILE FABRIC

Franco Casanova, Monza, Milan, Italy, assignor to South-Eastern Fabrics Corporation, New York, N. Y., a corporation of New York

Application July 5, 1941, Serial No. 102,218

Term of patent 7 years

To all whom it may concern:

Be it known that I, Franco Casanova, a citizen of Italy, residing in Monza (Milan), Italy, have invented a new, original, and ornamental Design for a Textile Fabric, of which the following is a specification, reference being had to the accompanying drawing, forming part thereof.

The figure is a plan view of a piece of textile fabric, showing my new design. The design unit is contained between the dot-and-dash lines, which unit is repeated in regular succession as indicated by the extensions beyond the unit boundaries.

I claim:

The ornamental design for a textile fabric, as shown and described.

FRANCO CASANOVA.
